CLAIM

The ornamental design for a touch panel docking station, as shown and described.

DESCRIPTION

FIG. 1 is a front view of one preferred embodiment of a touch panel docking station in accordance with the invention;

FIG. 2 is a front elevation of the touch panel docking station shown in FIG. 1;

FIG. 3 is a rear elevation of the touch panel docking station shown in FIG. 1;

FIG. 4 is a first side view of the touch panel docking station shown in FIG. 1;

FIG. 5 is second side view of the touch panel docking station shown in FIG. 1;

FIG. 6 is a bottom view of the touch panel docking station shown in FIG. 1;

FIG. 7 is a rear elevation of the touch panel docking station shown in FIG. 1 illustrating the placement of a power cord; and,

FIG. 8 is a bottom view of the touch panel docking station shown in FIG. 1 illustrating the placement of a power cord.

The portions shown in broken line are not claimed.
